Primary Examiner — Kendra Leslie Hamilton*Assistant Examiner* — Amanda Christensen(74) *Attorney, Agent, or Firm* — Capitol City TechLaw(57) **CLAIM**

The ornamental design for a signal transfer connector, as shown and described.

DESCRIPTION

FIG. 1 is a front, top, and right side perspective view of a signal transfer connector showing my new design;

FIG. 2 is a rear, top, and right side perspective view thereof;

FIG. 3 front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The equal-length broken lines in the drawings depict portions of the signal transfer connector that form no part of the claimed design. The dash-dot-dot lines define the boundaries of the claim.
